Guido M. Sacerdote

UNITED STATES PATENT OFFICE

GUIDO M. SACERDOTE, OF BAYSIDE, NEW YORK, ASSIGNOR TO BELKNAP McLAUGHLIN,
OF FLUSHING, NEW YORK

ADJUSTABLE ROLLING SCREEN

Application filed December 2, 1925. Serial No. 72,761.

This invention relates to rolling screens or shades, and more particularly refers to a novel and improved construction of frame, and to a novel arrangement for mounting a roller upon which the screen may be wound, whereby an adjustable structure results, which automatically adapts itself to any slight variations which may occur between window frames of the same stock size.

10 The primary object of this invention, is to provide a collapsible frame for rolling screens or shades, adapted to be adjusted within the limits of small variations which may occur in window frames of the stock size for which the screen or shade is intended.

15 A further object is to provide, in connection with a rolling screen or shade, a frame which may be adjusted within the limits of small variations which may occur in the 20 width of window frames of the stock size for which the screen is intended, said frame being also adjustable for similar variations in the sense of the height of said window frame.

Additional objects and advantages of the 25 present invention will more fully appear as the description proceeds, and will be set forth and claimed in the appended claims.

Rolling screens are generally composed of a frame, comprising a top or bottom casing 30 within which the screen roller is enclosed, and two side rails which act as guides for the edges of the screen, connected to said casing and secured to the inner surface of the window frame to which the screen is applied, by 35 means of screws or in any other suitable manner.

For the device to be effective, it is necessary that the frame be exactly of the same size as the opening in the window frame, because the necessity of producing a neat appearance bars the possibility of using packings or fillings in the clearance which may result if the screen frame is smaller than the window frame; and if the screen frame is 45 larger, then of course it cannot be inserted in position.

On the other hand, window frames are never exactly of the same size, and slight variations both in width and in height can 50 always be expected between window frames

of the same stock size. As a consequence, this entails the necessity of fitting the screen frames in place one by one, a rather expensive process which requires first the taking of accurate measurements, then the building of 55 each screen, and then the individual fitting by experienced men.

The fact that screens must often be placed at points distant from the source of production, coupled with the said necessity of giving 60 individual care to each screen, absolutely precludes quantity production and distribution, considerably limiting the possibilities of application of such devices, also because 65 the resulting cost is necessarily high.

Some attempts have been made to overcome this difficulty, by the production of collapsible frames, in which the roller casing or top rail (or bottom casing if the screen is arranged to extend upwardly instead of 70 downwardly), is composed of two telescopic members; but the appearance of the resulting device is not all that it should be, and furthermore the possibility of adjustment 75 cannot be limited to the frame, but must 80 perforce also extend to the roller and the operating mechanism. Also, the frame should be adjustable in the sense of its height, if a good fitting and a good appearance 85 have to be obtained.

The problem is somewhat complicated by the fact that the free end of the screen is generally provided with a cross member or bottom rail, with which are associated means for maintaining said bottom rail horizontal 85 throughout its travel, to insure the exertion of an evenly distributed and uniform tension for the entire width of the screen. This is necessary in order to prevent distortions or deformations in the structure of the screen 90 fabric, which is generally produced by open weaving of fine gauge metallic wires. The bottom rail and other parts mentioned, must of course also be capable of following the 95 adjustments of the frame one way or the other, without interfering with the proper operation and effectiveness of the device.

The present invention comprises a special construction of adjustable frame, whereby 100 any small variation in the width or height

of the window frame can be readily taken up, without sacrificing the symmetrical appearance of the device, or its effectiveness.

Fig. 1 is a fragmentary front view in elevation, partly sectioned, of the upper part of the frame;

Fig. 2 is a sectional side view in elevation of the same through line 2—2 of Fig. 5;

Fig. 3 is a similar view illustrating the frame adjusted for a slight increase in the height of the window frame; and

Fig. 4 is a detail plan sectional view of the same through line 4—4 of Fig. 5.

The screen frame forming the subject of this invention comprises, a roller casing or top rail 12, the length of which is not over the minimum allowable distance between the inner faces 72, 73, of the side rails 22, 23, the said side rails, and two corner members 74, 75 connecting each side rail to the top rail, so as to allow relative horizontal and vertical adjustment.

The side rails are in the form of a longitudinal casing of a section suitable to receive and conceal the chains and sprockets, and such other parts of the mechanism as the device may include; for instance, clamping means for the edges of the screen, such as described in another patent for "rolling screens," allowed to me July 7, 1925. Serial #1,545,282, or such as described in another application for patent on "clamping mechanism for rolling screens," filed simultaneously herewith. Said casing is formed with an inner longitudinal slot 76, through which are inserted and run one of the edges of the screen, and the corresponding end of the bottom rail.

The upper end of each side rail is formed with a part of its inner side cut off, and a part of its front side 77 unfolded or unbent as shown at 78, to remain flush with the upper portion of the outer side 79. The front end of the resulting extension 78 is cut off as at 80, or bent so that its edge or front surface is parallel to the rear side 81 of the rail.

The said upper end, is inserted from the side through a slot 82, cut at the bottom and at the outer end of its corresponding corner member, the rear surface of said upper end of the siderail, and the front edge of extension 78, registering with the inner ear and front surfaces of said corner member, designated by numerals 83, 84, respectively. Slot 82 is deep enough to cause the outer surface of the side rail to remain flush with the end surface of the corner member, when inserted within said slot; and the rear surface of said upper end of the side rail, and the front edge or surface of extension 78, together with the front and rear surfaces of the side rail proper, will form a sliding or telescoping connection of said side rail with

the corner member, allowing relative longitudinal adjustment of the said two parts.

The amount of adjustment thus made possible, is limited by the inner outline of the corner member, which is elongated from top to bottom enough to allow a certain play to the roller, which will of course be coaxial with hole 85, punched through the outer upper surface of the side rail, to receive the riveting end of stud 20. The lower front surface of said corner member is preferably rounded for the sake of appearance, and the quasi-rectangular vertical section of said corner member thus obtained will register and telescope within the top rail, which is made with a corresponding outline, as Figs. 6, 7, clearly show. The top rail is preferably composed of a front part 12 and a rear part 12', thus permitting an easy removal of the front part, for inspection purposes.

In this manner, a certain amount of relative adjustment between the top rail and the corner members, lengthwise of the top rail, that is, in the sense of the width of the frame, is made possible, so that the frame may be extended or contracted laterally to fit the width of the window frame; and after securing the top rail in position, by placing it with its upper surface against the upper surface of the window frame, and retaining it in said position by means of the corner members, which are screwed in place in any suitable manner, the side rails can be extended downwardly to the point where their lower end reaches the window sill, the roller and screen moving together with the side rails. The side rails are then secured to the sides of the window frame in any suitable manner.

The top rail may easily be set centrally of the resulting frame, by gauging or measuring the distance between the ends of the top rail and the inner surfaces of the side rails. Thus the frame will have a symmetric appearance, quite as neat as if the top rail were made in one piece extending all the way from one side to the other of the window frame.

The resulting construction clearly achieves the ends sought, without interfering with the appearance or the effectiveness of the device. The various parts of which the device is composed may therefore be produced by mass production methods, with the assurance that the same will fit any window of the size for which the device is intended, without the necessity of taking measurements, and without the necessity of employing expert labor for the setting up of the screen.

The arrangement described is new in screens adjustable in the sense of the width and has the advantage of permitting the employment of a roller of uniform diameter and of a single width of screen.

Rolling screens adjustable in the sense of their width in order to fit different widths of

window frames have been made and are old in the art; but the arrangement usually adopted includes a collapsible roller composed of two members telescoping into each other and two widths of screen overlapping at their inner edges; the arrangement obtained being therefore capable of adjustment between two relatively wide limits. The result is lack of uniformity in the diameter of the roller, lack of uniformity in the winding operation, and lack of uniformity in the general appearance of the screen, the section where the two edges overlap appearing darker than the rest; furthermore, lack of continuity of the screen surface nullifies outright the advantages which could otherwise be derived by clamping the edges of the screen in order to obtain a taut and uninterrupted surface.

On the other hand the arrangement described would not do for screens intended to be applied to window frames of different stock sizes; the idea being that an adjustable screen may be made for each stock size, capable of limited adjustment, to take care of such variations as may occur within reasonable limits, and such as actually occurring in practice.

The construction of frame illustrated, however, would lend itself equally well for use in connection with a collapsible roller and a two section screen in the sense of the width, if desired.

The drawings are mainly intended for illustrative purposes, and not in a limiting sense; since it is obvious that minor changes may be made in the construction of the device, without substantially departing from the inventive idea. Therefore, I reserve myself the right to carry my invention into practice in all those ways and manners which may enter, fairly, into the scope of the appended claims.

I claim:

1. In a device of the class described, the combination with two longitudinal side members, of means integral therewith for supporting a roller therebetween, and a transversal member interlocking with said two side members, providing a housing for said roller, said transversal member being adjustable longitudinally of said side members, independently of said roller.

2. In a device of the class described, the combination with two longitudinal side members, of means integral therewith for supporting a roller therebetween, and a transversal element comprising two end members interlocking with and adjustable longitudinally of said side members independently of said roller, and a casing for said roller, interlocking with and transversely adjustable in relation to said end members.
